BOILER AND FURNACE

Filed Jan. 14, 1929

UNITED STATES PATENT OFFICE

OTTO DE LORENZI, OF MAPLEWOOD, NEW JERSEY, ASSIGNOR TO INTERNATIONAL COMBUSTION ENGINEERING CORPORATION, OF NEW YORK, N. Y., A CORPORATION OF DELAWARE

BOILER AND FURNACE

Application filed January 14, 1929. Serial No. 332,243.

This invention relates to boilers and furnaces, and is especially useful where the fuel is employed in finely divided form, such, for example, as pulverized coal.

5 One of the objects of the invention is to prevent the slagging of refuse in an improved manner.

Another object of the invention is to make it possible to operate at very high ratings indeed, without encountering difficulties of the character hereinafter pointed out.

Still another object of the invention resides in the provision of an arrangement of boiler and a water wall lined combustion chamber 15 therefor in such a way as to secure effective circulation.

More specifically it is an object of my invention to provide a novel arrangement of cooling tubes for the bottom of a pulverized 20 coal burning furnace.

How the foregoing, together with such other objects and advantages as may herein-after appear, or are incident to my invention, are realized as illustrated in the accompanying 25 drawing, in which—

The figure is a vertical section through the preferred form of my invention.

Referring now to the figure, the reference character A denotes the boiler proper and B 30 the combustion chamber therefor. The boiler is of the double Ladd type and embodies two units a, b, each having an upper steam and water drum 7, a lower mud drum 8 and three banks of connecting tubes 9, 10, and 11, the 35 units being set opposite one another and above the combustion chamber B so that the gaseous products of combustion from the latter rise in the space between the two units and traverse the units in passes provided by the baffling shown.

40 A common steam drum 12 is located above the plane of the drums 7 and is connected to such drums by means of a multiplicity of tubes 13 whereby the velocity of the steam is cut down and dry steam ensured.

45 From the steam drum, steam is led to the group of headers 14 shown which are suitably connected to superheating elements (not shown).

The side walls of the combustion chamber 50 are defined by a water wall composed of three

portions 15, 16 and 17. The lower ends of the tubes of these portions connect with the headers 18 located externally of the combustion chamber; the upper ends of the portions 15 and 17 connect into the headers 19 and 55 20; and the upper ends of the tubes of the portions 16 connect into the header 21 located exteriorly of the combustion chamber. The header 18 is supplied by outside downcomers 22 each of which, at the bottom, has 60 a plurality of small pipes 22' connecting the lower ends of the downcomers 22 with the header 18. One of these downcomers 22 leads from the steam and water drum 7 of one of the units and the other downcomer 65 22' from the steam and water drum 7 of the other unit. The header 18 is also supplied by a group of downcomers 23 leading from the mud drum 8 of one unit and a similar group of downcomers 23' leading from the mud 70 drum of the other unit. The header 18 is also supplied by a portion of the tubes 24 of the row of tubes 25, the upper ends of which are connected with the mud drum 8 of one unit. There is another row of such 75 tubes 25 leading downwardly from the mud drum of the other unit and a number of such tubes 24 connected with the header 18. The remainder of the tubes of each row of tubes 25 lead to the header 26 located outside of 80 the bottom of the combustion chamber, this bottom being in the form of a double hopper. The lower end portions of the tubes which connect with the header 26 extend inwardly and downwardly and pass through the hoppers a short distance above the bottoms 85 thereof.

At a higher level I provide a slag screen C composed of two rows of horizontally inclined tubes 27 and 28. The tubes 27 incline 90 inwardly and downwardly from the header 29 to about the middle of the combustion chamber and thence they bend downwardly to pass outside of the combustion chamber to connect with the header 26. Similarly, the tubes 28 extend inwardly and downwardly from the header 30 for connection with the header 26. The tubes 27 and 28 are laterally spaced from one another so as to permit 95 gravitating ash to freely pass through the 100

space therebetween into the hoppers. Similarly, the tubes therebelow are spaced for the same purpose. Preferably the tubes 27 and 28 have their inner ends extended past one another so as to give maximum cooling effect near the center of the combustion chamber.

Rising from the header 29 is a water wall composed of a row of tubes 31, the upper ends of which tubes are connected into the header 32, which header, in turn, has connected thereto the lower ends of the arch tubes 33, which tubes serve to support the arch 34 and to line the throat 35. The upper ends of the tubes 33 are connected with tubes of the banks 15 of tubes of the left hand unit by means of the connectors 36 inside the drum 8 of that unit.

There is a similar water wall of tubes 31 rising from the header 30 to the header 32, 20 from which arch tubes 33, as before, lead for delivery to tubes of one of the banks of tubes of the other unit.

I prefer to have the arch tubes connected with the first row of the second bank of tubes.

25 The headers 21 of the side water walls are connected by risers 37 to the steam and water drums 7 of the two units.

From the foregoing it will be seen that water supply for the screens and water walls 30 is taken not only from the steam and water drums, but also from the mud drums; and that the delivery from the water walls is divided, approximately half going to one of the steam and water drums and the other half 35 to the other steam and water drum.

It will also be observed that I use a portion of the downcomers for the slag screen as a means for further cooling refuse by the absorption of heat from the bottom of the combustion chamber. I am enabled to do this without incurring any circulation difficulties by virtue of the high head of water above the header 26 which is practically the low point of the entire installation.

45 By utilizing these downcomers for effecting cooling, I am enabled to operate at extremely high rates without causing fusion of the refuse into a molten mass difficult to remove without shutting down the furnace. The space which must necessarily be provided between the tubes 27 and 28 imposes a limitation upon the number of tubes that can be employed, and, of course, the cooling effect of such tubes is dependent upon 50 their number. Hence, such tubes, of themselves, are insufficient to secure the desired cooling of the refuse when operating at extremely high rates.

Owing to the large number of tubes in the 60 installation subject to radiant heat, a great proportion of the steam is generated in such tubes, and there is very rapid circulation therethrough. The taking of the water supply for such tubes in part from the steam and water drums and in part from the mud drums

ensures the maintenance of proper water levels in the steam and water drums, cuts down the ebullition, and tends to secure the delivery of drier steam to the steam drum 12.

The fact that there is a rapid circulation 70 and a heavy "pull" through the upright water walls connected with the slag screen assists in making it possible to use the down-comers as a cooling means in the bottom of the furnace.

75 The furnace may be fired downwardly through the arches or by means of burners located at the corners preferably in the lower part of the combustion chamber and arranged to fire tangentially.

I claim:—

1. In combination, a substantially upright boiler, a combustion chamber therefor therebelow, a slag screen above the bottom of the chamber for cooling refuse comprising two 85 rows of spaced tubes, each row extending inwardly and downwardly from one of two opposite sides of the chamber to about the center thereof and to the exterior, a header for the lower ends of the said tubes, upcomer means leading from the upper ends of said tubes to the boiler, and downcomer means from the boiler to said header comprising tubes arranged below the slag screen tubes to absorb heat to assist in cooling refuse. 95

2. In combination, a double Ladd type of boiler, each unit having an upper drum and a lower drum with connecting tube banks, a combustion chamber below, upright water wall tubes defining the four upright sides 100 of the chamber, upcomer connections therefor dividing the delivery from such tubes between the two upper drums and delivering to steam space thereof, and downcomer means therefor connected to supply part of 105 the water walls from the upper and the lower drums of one unit and to supply the other remaining part from the upper and lower drums of the other unit, together with a steam drum common to both upper drums. 110

3. In combination, a combustion chamber, a substantially upright boiler disposed at least in part above the chamber and having water header means arranged adjacent the top of the chamber, a slag screen for cooling refuse particles including a row of spaced tubes in the lower part of the chamber above the bottom thereof, upcomer means connecting said tubes with the boiler, and downcomer means leading downwardly from said header means to the low point of said tubes, said downcomer means being disposed partly within the chamber in position to assist in cooling refuse. 115

4. In combination, a combustion chamber, a substantially upright boiler disposed at least in part above the chamber and having water header means arranged adjacent the top of the chamber, a slag screen for cooling refuse particles including a row of 120 tubes in the lower part of the chamber above the bottom thereof, upcomer means connecting said tubes with the boiler, and downcomer means leading downwardly from said header means to the low point of said tubes, said downcomer means being disposed partly within the chamber in position to assist in cooling refuse. 125

130

spaced tubes in the lower part of the chamber above the bottom thereof, upcomer means connecting said tubes with the boiler, and downcomer means leading downwardly from said header means to the low point of said tubes, said downcomer means having portions inclined downwardly with respect to the direction of circulation therethrough, and said portions being disposed within the chamber in position to assist in cooling refuse and being connected with said tubes adjacent the low point thereof.

In testimony whereof I have hereunto signed my name.

OTTO DE LORENZI.
